UNITED STATES PATENT OFFICE.

THOMAS A. SEARLE, OF QUIDNICK, ASSIGNOR TO ROBERT BARTON, OF PROVIDENCE, RHODE ISLAND.

BUTTON OR STUD.

SPECIFICATION forming part of Letters Patent No. 281,404, dated July 17, 1883.

Application filed April 30, 1883. (No model.)

To all whom it may concern:

Be it known that I, THOMAS A. SEARLE, of Quidnick, in the county of Kent and State of Rhode Island, have invented a new and useful Improvement in Buttons or Studs; and I do hereby declare the following specification, taken in connection with the accompanying drawings, forming a part of the same, to be a description thereof.

10 This invention consists in a button or stud the back of which is composed of an arm bent into substantially an L shape, and rigidly secured to the button-head, and a second arm, similarly shaped, which is pivoted to the button-head or to the base of the first arm, and has its pivotal end engaged by a spring or springs located in the button-head, whereby said arm is held in a position to retain the button in place, and also in position for the 20 back to be inserted into the button-holes, as will hereinafter appear.

Referring to the drawings, Figure 1 represents a rear view of a button embodying the invention, with the arms in position to retain the button in place. Fig. 2 shows a rear view of the button with the arms in position to be inserted into the button-holes. Figs. 3 and 4 represent side elevations of the button with the arms in the two said positions, respectively. Fig. 5 shows in perspective the back plate of the button-head. Fig. 6 represents in perspective the movable arm. Fig. 7 shows the button being applied. Figs. 8 and 9 represent rear views of a modification, with the 35 arms in different positions. Fig. 10 shows the back plate of the head of such button. Fig. 11 represents the movable arm of such button.

A is the button-head, of any preferred shape, which is provided with a back plate, A', secured thereto. As particularly shown in Fig. 5, the inner surface of this plate is countersunk, so as to produce ears a, having cavities a'. To these ears an arm, B, is rigidly secured, the said arm being bifurcated and bent 45 into substantially an L shape. The cavities a' in the plate A' form a bearing for the pivotal pin b of an arm, B', which is hinged to the button-head, so as to swing between the legs of the arm B from the position shown

in Figs. 1 and 3 to that shown in Figs. 2 and 50 4. As particularly shown in Figs. 3 and 4, the pivotal end of the arm B' is enlarged, and the face b' of said end is substantially at right angles to the face b. A spring, C, is located in the button-head, and bears at its ends on 55 depressions in the plate A', and at its center on the pivotal end of the arm B', with which it is always in engagement, thereby holding said arm, by contact with the face b', in the position shown in Figs. 1 and 3, and also holding 60 said arm, by contact with the face b', in the position shown in Figs. 2, 4, and 5.

The arm B' being in the position shown in Figs. 2, 4, and 5, the button is applied by inserting the free end of the arm B into the 65 button-holes and bringing the button-head into an inclined position, as shown in Fig. 5, so that as the button-head is pressed toward the article to which the button is being applied, and is gradually brought parallel with such 70 article, as shown by dotted lines, the arm B' will pass through the button-holes and assume the position shown in Figs. 1 and 3, and thereby hold the button against accidental detachment.

In Figs. 8 and 9 a modification is shown in which the swinging arm B' is bifurcated, (instead of the arm B,) and two springs C are employed to engage its pivotal ends. The pivotal pin b takes bearing in a single ear, a, 80 formed on the plate A', as shown in Fig. 10, to which ear the arm B is secured. The action of this button is substantially the same as already described.

Although I prefer to provide the plate A' 85 with an ear or ears, a, to which the arm B is secured and in which the arm B' is pivoted, yet, if desired, the plate A' may be without ears, and the arm B be secured to the plate, and the arm B' be pivoted to the arm B, near 90 the base of the latter, in a manner easily to be understood.

What I claim, and desire to secure by Letters Patent, is—

1. A button or stud having a head, a bent 95 arm, B, rigidly secured thereto, a swinging arm, B', pivoted to the button-head or to the arm B, and provided with a cam-shaped end,

and a spring or springs, C, located in the button-head, and adapted to engage the cam-shaped end of the arm B' and hold it open or closed, substantially as set forth.

5. 2. A button or stud having a head provided with a back plate, A', furnished with an ear or ears, a, a bent arm, B, secured to said plate in a fixed position, a swinging arm, B', pivoted in the ear or ears a, and having an enlarged

end with faces b' and b², and a spring or springs 10 C, located in the button-head, engaging the pivotal end of the arm B' and holding said arm in its two positions, substantially as described and shown.

THOMAS A. SEARLE.
